UNITED STATES PATENT OFFICE.

JAMES BIDWELL MILLS, OF TORONTO, ONTARIO, CANADA.

FOUNTAIN BRUSH.

Application filed December 6, 1924. Serial No. 754,400.

To all whom it may concern:

Be it known that I, JAMES BIDWELL MILLS, a subject of the King of Great Britain, residing at the city of Toronto, in the Province of Ontario, in the Dominion of Canada, have invented new and useful Improvements in Fountain Brushes, of which the following is a specification.

The invention relates to improvements in fountain brushes as described in the present specification and shown in the accompanying drawings which form part of the same.

The invention has for its object the provision of a new and useful fountain brush for the purpose of cleaning motor cars and the like; one which is simple in construction and serviceable in operation.

A very distinctive feature of this invention resides in the construction and arrangement of means for preventing water from running onto its handle and the hand of the user.

The invention consists essentially of a comparatively long tubular rod having a grip or handle portion arranged to connect with a source of water supply and a perforated section for spraying water received from the source onto a brush element; an arrangement of collars are provided intermediate of said handle and brush in order to prevent water running onto the former and thence upon the person of the user.

Referring to the drawings, Figure 1 is an elevation of the device.

Figure 2 is a cross sectional view taken on the line 2—2 of Figure 1 showing the mode of anchoring the rear end of the brush element to the rod.

Figure 3 is a side elevation of the device partly in section depicting the collars and handle and the brush in outline only.

Figure 4 is a transverse section similar to that taken on the line 2—2 of Figure 1 illustrating a further method of fastening the rear end of the brush element to the rod.

Like numerals of reference indicate corresponding parts in each figure throughout the drawings.

In the drawings, the numeral 1 indicates the tubular rod which is closed at one end and open at the other. Its open end is provided with a coupling 2 of a conventional character for the purpose of enabling it to be readily connected to a hose. Commencing at its closed end and extending past its longi-

tudinal centre are a series of perforations 3, said openings being disposed on opposing sides thereof. This perforated section constitutes the brush-sprayer.

The remaining imperforate portion of the rod is provided with a sleeve 4 of rubber or like material in order to form a handle. This sleeve is preferably constructed of a lesser diameter than that of the rod and stretched thereover, thus frictionally gripping the same and dispensing with the use of more expensive modes of attachment.

Situated in advance of the handle or hand-grip 4 are a pair of spaced rubber collars 5 of a relatively large external diameter, and spacing these collars is a resilient band 6 of like material.

Fixedly secured in the closed end of the rod is a hook 7 which cooperates with the band just mentioned in attaching the brush element to the rod.

8 is the brush element comprising a rigid substantially U-shaped core 9 of twisted wire having its extremities inwardly offset, as at 10, in order to make them contiguous with the rod 1. Said brush element is mounted upon the sprayer by forcing its extremities 10 between the elastic band 6 and the wall of the rod 1, the frontal collar being also stretched over these extremities (see Fig. 2). The opposing end of the brush is then secured by placing its bight 11 in the hook 7 and closing the same in order to make the connection permanent.

Whereas the invention is shown and described in its application to a brush element it is obvious that it is equally susceptible of being used with a mop or other analogous device. Hence the term brush element is intended to be read synonymously with a mop, or that which may reasonably be deemed to be an equivalent therefor.

It will be observed that while the brush extremities 10 are securely held against detachment by the tension of the band 6, there may be a tendency on their part to shift around the rod itself. Hence, to overcome this tendency, a device illustrated in Fig. 4 is employed, which consists in piercing the opposing walls of the rod 1 in the vicinity of the band 6 and threading a wire 12 therethrough. The ends of the wire are then bent around the extremities 10 of the brush core 9.

In the use of the invention, the coupling 2 is connected to a hose and the water turned

on. The water is conducted through the rod to the perforations 3 whence it is sprayed on the brush element 8 which is conveniently wielded by the handle 4 as the water is supplied by the sprayer.

What I claim is:—

1. In a device of the class described, a tubular rod having one end open and the other closed, a coupling carried by its open end for connection to a hose, the closed end being provided with a multiplicity of perforations in its wall, said openings extending a considerable distance along its length and constituting a sprayer, a sleeve encircling the imperforate portion of the rod forming a handle, a pair of spaced collars fitted over the rod in advance of said sleeve, an elastic band spacing the same, a hook projecting from the closed end of said rod, a brush element mounted over the sprayer, said brush element comprising a rigid U-shaped core, said core being attached to the rod at one end by placing its bight in the hook and closing the same, and at the opposing end by inserting its extremities between the elastic band and the wall of the rod; and means cooperating with said band in order to prevent the extremities of the core from shifting.
2. In a device of the class described, a tubular rod having one end open and the

other closed, a coupling carried by its open end for connection to a hose, the closed end being provided with a multiplicity of perforations in its wall, said openings extending a considerable distance along its length 30 and constituting a sprayer, a sleeve encircling the imperforate portion of the rod forming a handle, a pair of spaced collars fitted over the rod in advance of said sleeve, an elastic band spacing the same, a hook 35 projecting from the closed end of said rod, a brush element mounted over the sprayer, said brush element comprising a rigid U-shaped core, said core being attached to the rod at one end by placing its bight in the 40 hook and closing the same, and at the opposing end by inserting its extremities between the elastic band and the wall of the rod; and means cooperating with said band in order to prevent the extremities of the 45 core from shifting.

Signed at the city of Toronto, in the Province of Ontario, in the Dominion of Canada, this 4th day of December, 1924

JAMES BIDWELL MILLS.
